UNITED STATES PATENT OFFICE.

GEORGE W. SMITH, OF DAYTON, OHIO, ASSIGNOR TO AMERICAN BURNER COMPANY, OF BUFFALO, NEW YORK, A CORPORATION OF DELAWARE.

OIL-BURNER.

1,254,283.

Specification of Letters Patent. Patented Jan. 22, 1918.

Application filed January 22, 1917. Serial No. 143,742.

To all whom it may concern:

Be it known that I, GEORGE W. SMITH, a citizen of the United States, residing at Dayton, in the county of Montgomery and State of Ohio, have invented certain new and useful Improvements in Oil-Burners; and I do declare the following to be a full, clear, and exact description of the invention, such as will enable others skilled in the art to which it appertains to make and use the same.

This invention relates to improvements in burners, particularly those which use fuel oil such as kerosene, and are adapted to be placed in the fire box of a stove.

The principal object of the invention is to provide a very simply constructed, efficient, durable, and inexpensive device of this character.

An additional object is to provide a device having a base upon which several forms of burners may be used, the latter being interchangeable.

Still another object is to provide a novel form of burner for the device which will be more efficient than those of ordinary construction.

With these and other objects in view, the invention resides in the novel features of construction, combination and arrangement of parts which will be hereinafter more particularly described and claimed, and shown in the drawings wherein;

Figure 1 is a vertical sectional view through a stove of ordinary construction showing my improved burner mounted in the fire box thereof;

Fig. 2 is a plan view partly in section as seen along the line 2—2 of Fig. 1;

Fig. 3 is a horizontal section taken on the line 3—3 of Fig. 1;

Fig. 4 is a vertical transverse section taken substantially on the plane of the line 4—4 of Fig. 1;

Fig. 5 is a detail horizontal section through one end of the main burner;

Figs. 6 and 7 are transverse sections taken respectively on the lines 6—6 and 7—7 of Fig. 5;

Fig. 8 is a detail longitudinal section through a portion of the generator tube;

Fig. 9 is a horizontal section through the

generating member showing more particularly the interior construction thereof;

Fig. 10 is a side elevation of a modified form of burner head which may be used with the other parts of this invention;

Fig. 11 is a plan view of the burner shown in Fig. 10;

Fig. 12 is a vertical transverse section on the line 12—12 of Fig. 11;

Fig. 13 is a plan view of still another form of burner head;

Fig. 14 is a side elevation of the last mentioned burner head;

Fig. 15 is a plan view of a burner head somewhat similar to that illustrated in Figs. 13 and 14; and

Fig. 16 is a side elevation of the burner illustrated in Fig. 15.

As hereinbefore mentioned, the invention is designed to be placed upon a grate within the fire box of a stove, and the burners are so arranged that the plates at the top of the stove and also the oven will be effectively and thoroughly heated.

The invention comprises broadly a body member in which a liquid fuel is vaporized, a base for supporting said body, said base resting upon the grate, and the burner proper, the latter being carried by the body and receiving the vaporized fuel of the generator.

The body member designated by the numeral 1 is substantially J-shaped in plan view, it having a long arm 2 and a relatively short arm 3, the former being provided with a pair of bosses 4 and 5, one being disposed above and the other below said arm at its free end. The lower boss 4 is formed integral with or otherwise connected to a base 6, while the other boss 5 has a central aperture formed therein through which the fuel passes from the body member to a burner B detachably connected therewith. In Figs. 1 and 2 it will be seen that the arms of the body member are disposed substantially horizontal, and that the burner B which is positioned over the long arm 2 is in a similar plane.

The free end of the short arm 3 is enlarged as shown at 8 to form a mixing chamber, the bottom of said enlarged portion being provided with an air inlet 9, while the

gas from the generator G enters through one side at the point 11. It will also be seen that the base 6 extends beyond said end of the arm 2 and underlies the generator G, 5 this part forming a heating pan 12. One end of the generator is supported by an ear 13 projecting from the base.

The generator G, the construction of which is clearly illustrated in Fig. 9, consists of a pair of parallel spaced pipes 14 and 15, the pipe 14 being termed, for the sake of convenience, the generating pipe, while the pipe 15 will be known as a super-heating pipe. In forming this generator G, 10 15 a substantially H-shaped coupling 16 is provided; the main or leg portions 17 and 18 of this coupling being connected by a short cross pipe 19 in which is disposed a series of fine wire gauze screens 20. Also positioned 20 between and formed integrally with the main portions 17 and 18 is an attaching ear 21 by means of which the generator is connected to the ear 13 on the base 6. The outer end of each portion 17 and 18 is internally 25 screw threaded, and in one end of the portion 17 is threaded a valved plug 22, the same having a passageway therethrough which connects the interior of the coupling with a pipe 23 extending from the source of 30 fuel supply; the valve 24 controls the flow of liquid fuel from the pipe 23 to the other part of the generator.

The above mentioned generating pipe 14 is threaded in the other end of the portion 35 17 of the coupling 16, the outer end of said pipe being closed by a plug 25. Within the pipe 14 and in the portion 17 of the coupling is disposed an inner tube 26, one end of 40 which is connected to the inner end of the plug 22 and communicates with the passageway thereof, while the other end is open and terminates at a point spaced from the plug 25. Surrounding this inner tube 26 within the pipe 14 is a porous fire-resisting packing 45 27 which is preferably asbestos. It will be noted that as the liquid fuel flows from the supply pipe 23 past the valve 24 and into the passageway of the plug 22, it must enter the inner tube 26. It passes through this tube 50 and out the open end thereof, from whence it circulates through the porous packing 27 to the cross pipe 19 which is at the opposite end of the generator from the open end of the inner tube 26. As this liquid fuel is 55 passing through these parts, heat which is generated in a manner hereinafter to be set forth, causes the same to become vaporized before it reaches the pipe 19.

This gaseous fuel and any liquid fuel 60 which has not yet been vaporized is carried along therewith through the gauze screens 20 and into the other leg 18 of the coupling 16. These screens 20 effectively remove any carbon which may have been formed within 65 the pipe 14. From the portion 18 of the

coupling the gas enters the superheating pipe 15 which is connected to one end of this part 18. The other end of this part of the coupling is closed by a stuffing box 28. The end of the pipe 15, which is considerably 70 longer than the pipe 14 as evident from the several figures of the drawings, is connected to the mixing chamber 8 and the entrance of the gaseous fuel from the pipe 15 into the mixing chamber is controlled by a valve 29. 75

The seat for this valve is formed in a connecting member 30 which is carried by the end of the pipe 15 and joins the same to the mixing chamber. The stem 31 for the valve 29 extends throughout the length of the pipe 80 15 and through the stuffing box 28. By providing this long valve stem it is obvious that any carbon which may collect within the intermediate portions of the pipe 15 may be readily removed. In order to prevent the 85 portion of the pipe 15 adjacent the valve 29 from being clogged with carbon, a coil 32 of aluminum wire is disposed around the valve stem 31, as shown in Figs. 8 and 9. It has been found by practical experiment 90 that a coil formed of this kind of wire will not collect carbon as will coils of other metals, therefore it is unnecessary to clean the pipe except at long intervals. Even though small particles of carbon collect on 95 the wire, the same are readily blown off by a blast of gas through the pipe. For this reason aluminum is used in place of the usual asbestos filler.

As shown in the drawings, the parts of 100 the generator G are disposed horizontally over the heating pan 12, so that in starting the operation of the device both pipes 14 and 15 may be equally heated, thereby more quickly generating gas for use in the burner 105 B. Since it is necessary to continuously generate gas for use in the burner B when the device is in operation, a supplemental burner 33 is provided, the same consisting of a pair of pipe sections 34, one of which 110 is connected to each side of a T-coupling 35. The latter coupling is connected to the end of the body member 1 adjacent the bosses 4 and 5 by means of the elbow 36.

From Figs. 2 and 3 it will be seen that this 115 supplemental burner 33 extends parallel to the arms of the body member 1 and between the same, and also parallel to the generating pipe 14 of the generator G, said pipe being preferably arranged in close proximity to 120 the slits 37 in one side of the pipe sections 34. Thus it will be seen that some of the gas which is generated and passed through the body member 1 enters the main burner B through the pipe connecting the same 125 with the boss 5, while the other passes into the supplemental burner 33 and throws its flame in a direction to envelop the pipes 14 and 15. The invention is also preferably arranged in the fire box of the stove in such 130

a position that the heat from the supplemental burner 33 in addition to heating the generator, will also heat the oven of the stove.

5 The operation of the burner is readily evident from the drawings, but briefly described is as follows:—In first starting the device a quantity of liquid fuel is poured into the heating pan 12 through the inlet pipe 12', and this fuel is ignited so as to vaporize the liquid fuel which flows into the generator pipe 14 when the valve 24 is opened. After the oil or other fuel in the pan 12 has burnt itself out, or after sufficient gas has been generated in the pipes 14 and 15, the valve 29 is opened, thereby allowing this newly generated gas to flow into the body member 1 from whence it is distributed to the two burners. The generation 20 of a new supply of gaseous fuel is maintained by the heat from the supplemental burner 33 as above set forth.

With the construction above described, any preferred form of main burner G may 25 be used, several being illustrated in the present application. In Figs. 1, 4, 5, 6 and 7 is illustrated one form of burner which may be attached to the boss 5. This burner consists of a cylindrical tubular member 38, its opposite ends being open to receive the outer ends of an air circulation pipe 39 which extends throughout the length thereof. The ends of this pipe 39 are externally threaded 30 to receive the nuts 40 which, when threaded on the pipe 39 bear against washers 41 which serve to close the ends of the outer pipe 38 and render said ends gas tight. The gaseous fuel from the body member enters the outer pipe around the air inlet pipe 39 through 35 the nipple 42. The opposite sides of this outer pipe 38 are provided with a plurality of vertical slits 43 which form burner openings, through which the gas flows. It will be noted, particularly from Fig. 5, that each 40 of these slits is formed in a rib 44 which projects from the side of the pipe, the inner portions of the ribs being cored out as shown at 45. The provision of the air circulation pipe 39 prevents the burner from overheating, since a continuous flow of cool air may 45 pass through the center of the burner and between the two series of burner openings.

In Figs. 10 to 16 is illustrated an additional form of burner which may be connected to the body member of the device, these figures illustrating three different methods of constructing this modified form of burner. In each of the three variations of the burner illustrated in these figures, the 50 heads H are preferably spaced from the body member by means of an upright pipe 46, the length of which depends upon the type of stove and the height of the fire box in which the invention is placed. In stoves 55 which are primarily adapted for heating, the

fire boxes are rather tall, and in such a case the upright pipe 46 will be rather long. A cross or branch pipe 47 is connected to the upper end of the upright pipe 46, and is adapted to have secured to each end one of 70 the heads H.

All of these heads H are formed substantially alike although some are straight, and others curved to a greater or less extent. The inner faces of the heads, which are tubular, are concaved as shown at 48, thus providing a greater cooling surface to be reached by cool air to prevent the overheating of the burner. The same principle is employed in these burners as in the first 75 mentioned burner having the air circulation pipe 39. The outer faces of the heads H are each provided with two series of vertical slits 49 which form burner openings. Each series of burner openings extends from the 80 end of the head to a point spaced from the inlet opening which is formed intermediate the ends thereof. This arrangement provides a space 50 opposite the opening in each head H in which there are no burner 85 openings, thereby more evenly distributing the gas which enters the heads from the branch pipes 47. It is obvious that if the slits were formed in this portion 50, a greater quantity of gas would be forced 90 through the same than through those openings toward the end of the head.

I claim:—

1. In a device of the class described, a body member comprising a J-shaped pipe, 100 the arms thereof being parallel and disposed in the same horizontal plane, a base secured to the body member, a burner mounted on one of the arms of said member, an elongated gas generating tube of relatively small 105 diameter secured to the other arm of said body member at one end, an H-shaped coupling pipe at the opposite end of said tube, a second tube closed at one end and connected at the opposite end to said coupling 110 and extending in parallel relation to said first tube, an auxiliary burner on an arm of said J-shaped pipe adjacent one of the tubes, oil flow retarding material in one of said tubes and gas superheating means in the 115 other, an oil supply valve in one arm of said coupling, a gas controlling valve in the other arm, and a priming pan in said base below said tubes.

2. In a device of the class described, a 120 body member comprising a substantially J-shaped pipe, a pair of bosses extending in opposite directions from the long arm thereof adjacent its free end, a base secured to one of said bosses, a burner mounted on the 125 other boss, and a gas generating member connected with the short arm of the body member.

3. In a device of the class described, a body member comprising a substantially J- 130

shaped pipe, a pair of bosses extending in opposite directions from said body member, a base secured to one of said bosses, a main burner mounted on the other boss and disposed above the body member, a gas generating member connected with the body member, and a supplemental burner positioned below the main burner to throw its flame against said gas generating member.

10 4. In a device of the class described, a body member, a base connected to said body member for supporting the same, a burner mounted upon said body member, a gas superheating tube connected to the body member, a valve in said gas superheating tube to control the flow of gas into said body member, a second gas generating tube connected with said superheating tube and a valve therein to control the flow of liquid 20 fuel.

5. In a device of the class described, a base, a body member connected to said base, a burner on the body member, a gas generating tube connected to the body member, 25 a valve in said tube to control the flow of gas into said body member, and a helical coil of aluminum wire surrounding the stem of said valve within the tube, whereby to prevent the formation of carbonaceous 30 deposits in said gas generating tube.

6. In a device of the class described, a base, a body member connected to said base, a burner on the body member, a gas generating member comprising a pair of spaced 35 parallel pipes, one being a generating pipe and the other a superheating pipe, a valved inlet in one end of the generating pipe, the other end thereof being closed, an inner tube in said pipe and having one end connected 40 to the valved inlet, an outlet valve in one end of the superheating pipe, said end being connected to the end of said body member, a stuffing box closing the other end of the

superheating pipe, a connection between the two pipes, and means for heating said generating pipe. 45

7. In a device of the class described, a base, a body member connected to said base, a burner on the body member, a gas generating member comprising in combination, a 50 substantially H-shaped coupling, a valved inlet plug in one end of one leg of said coupling, a generating pipe in the other end of said leg, an inner tube disposed in said generating pipe and having one end connected to said plug, the other end being spaced from the outer end of the generating pipe, a superheating pipe connected to one end of the other leg of said coupling, a stuffing box closing the other end of said 60 leg, an outlet valve in the outer end of the superheating pipe, said end of the pipe being connected with the body member, and a screen in the passageway between the legs of said coupling. 65

8. In a device of the class described, a gas generating member, a gas supply pipe extending from said member, a branch pipe connected intermediate its ends to the end of said supply pipe, and an elongated tubular burner member on each end of the branch pipe, the ends of said branch pipe entering the burner members intermediate their ends, said burner members each having a pair of series of burner openings in their outer 75 faces, the inner openings of said series being spaced from the ends of said branch pipe. 70

In testimony whereof I have hereunto set my hand in the presence of two subscribing 80 witnesses.

GEORGE W. SMITH.
